Attorneys.

UNITED STATES PATENT OFFICE.

EDWIN L. HENDERSON, OF NORWOOD, OHIO, ASSIGNOR TO THE KEMPER THOMAS COMPANY, OF NORWOOD, OHIO, A CORPORATION OF OHIO.

BAG.

1,400,499.

Specification of Letters Patent.

Patented Dec. 13, 1921.

Application filed June 27, 1919. Serial No. 307,143.

To all whom it may concern:

Be it known that I, EDWIN L. HENDERSON, a citizen of the United States, and a resident of the city of Norwood, in the county 5 of Hamilton and State of Ohio, have invented certain new and useful Improvements in Bags, of which the following is a full, clear, and exact description, reference being had to the drawings accompanying 10 this specification.

My invention relates to the manufacture of bags in general, and more particularly to bags made of fabric and having handles therefor. The main reason why my invention 15 is applicable to fabric bags is because the strength of the construction makes it especially valuable where used with materials which need considerable reinforcement. It would be as readily available for 20 leather bags as will be observed from the specification to follow.

Among other objects of my invention are the provision of a means for carrying the load of the container portion thereof on 25 binding strips in a specially durable and simple manner, said binding strips being brought together and stitched into the form of a handle, or shoulder strap, as the case may be.

The bag, as shown in the drawings is a newspaper bag or satchel in which the container portion is left open along one end to permit of the easy insertion and withdrawal of newspapers without removing the bag from the shoulder strap. It will be understood, however, that the bag could readily be closed at both ends, thereby becoming 35 adaptable for a variety of uses, such as a mail carrier's bag. When open at the end 40 the device is also quite valuable for the workman who carries a variety of large tools with him during his work, as the feature a ready availability of the contents of the bag will be a value in this instance 45 also.

The object of my invention is generally to provide a very strong and durable satchel or bag, having a handle or shoulder strap, and this I accomplish by that certain construction and arrangement of parts to be hereinafter more specifically pointed out and claimed, wherein among other things, a continuous double strip of tape or binding ma-

terial is employed to not only brace the bag, but provide the handle therefor.

55

In the drawings,

Figure 1 is a perspective view of the device.

Fig. 2 is a vertical sectional view taken through the center thereof on line 2, 2.

60

It will be noted that the container portion of the device is formed with two sides, 1 and 2, a bottom 3 and one end 4. If desired the other could be inserted also, to form a completely closed receptacle except 65 at the top, without effecting my invention herein. The container portion may be made of stout fabric, such as canvas or duck, or of such other material that is desired. The parts, as shown are stitched together, along 70 all of the folds although the two sides and the base are made of one piece bent in a triple fold, and stitched at the folded edges, so as to make the base of the bag stand out, when the bag is empty, as a matter of convenience. This latter feature is not a necessity.

75

The binding strip is started at 5, leaving enough to extend part way of the shoulder strap, and is stitched double. At 6 the two 80 portions of the strip are separated forming single strips 7 which are stitched together with the material of the container portion between them clear down one side around the base and back up the other side of the 85 said container. At the upper edge of the other side of the container the strips are united directly to each other again at 8 and preferably allowed to extend a short distance so as not to close tightly the open 90 mouth of the container. At 9, the double strip is united to the original section and the two double strips are stitched together, until the original portion has been entirely 95 stitched to the running portion thereof. The running portion is then extended sufficiently to make a shoulder strap of the desired length, and brought to the side of the container, at the far end of the bag from the first attachment at 6 and again separated 100 at 10 to include the material of the container.

It is brought down around the container, back up and united again at 11, just as at the other end of the device, and is again united to form a four ply tape at 12. The 105 running portion is then stitched to the non-

quadruple portion of the tape, and finally overlapped at 13, to form a six ply portion for the central portion of the handle or shoulder strap.

5. It can be readily observed that there is no strain on the fabric or other material of the bag at the point of attachment of the straps, and that the whole weight of the 10 contents of the bag is sustained by the straps, if it is of sufficient length. But one double strip of binding serves the entire function of providing the re-inforcement, and weight sustaining member of the bag, and serves as a handle or shoulder strap, at 15 the same time. The strap which is subjected to the most wear is four ply throughout, except at the central portion, where greatest wear occurs, and there is preferably six ply.

The two ends of the binding strip or tape 20 could, of course, be abutted instead of overlapped, without destroying the value of the invention, although the overlapping structure is the preferred one.

The method of holding the upper edges 25 of the container together the desired amount by regulating the distance between the upper edges of the bag and the unions at 12 and 9, is a valuable feature, as is the method of attachment of the binding strip along the 30 edges of the container portion, so as to leave an extended shoulder strap or handle running practically the length of the device.

Double and quadruple are relative terms based on the considering of the portions 35 when separated to go around the bag, as single.

Having thus described my invention what I claim as new and desire to secure by Letters Patent is:—

40. 1. In a device of the character described, a container portion, and a continuous binder therefor, extending around the sides and base of the said container at the ends thereof on the inside and outside thereof, and united outside of the open end of the container to form a handle whereby the strain of attachment of the handle to the container is done away with and the binder supports by itself the weight sustained by it.

45. 2. In a device of the character described, the combination with a container portion of a continuous binding strip doubled outside of the container portion, and separated and stitched together around the container with 50 the container portions between the sections thereof, said binding strip serving as a han-

dle for the container whereby all tearing strain on the handle is eliminated and transferred to the binding strip.

3. In a device of the character described 60 the combination with a container portion of a continuous binding strip doubled outside of the container and separated and stitched together around the container with the container portion between the sections thereof, 65 this operation being performed at both ends of the container, and the doubled portions of the strip secured together outside of the container, thereby forming a handle and relieving the container of any weight impinging 70 on the binding strip and transferring strains on the container to the binding strip prior to reaching the handle.

4. In a device of the character described 75 the combination with a container portion of 80 a binding strip doubled outside of the container and separated and stitched together around the container with the container portion between the sections thereof, this operation being performed at both ends of the container, and the doubled portions of the strip secured together outside of the container, thereby forming a handle, with the points of attachment of the doubled portions being spaced away from the upper edge of 85 the mouth of the container, for the purpose described.

5. In combination with a bag or container portion having sides and a bottom, a binding strip element stitched thereto and to 90 itself, to form single portions stitched in loops around the bag, with the material of the bag between the said single portions, double portions extending from the bag to the handle or shoulder strap portion, and 95 quadruple portions throughout the said handle or strap portion for the purpose described.

6. In combination with a bag or container portion having sides and a bottom, a binding strip element stitched thereto and to 100 itself, to form single portions stitched in loops around the bag, with the material of the bag between the said single portions, double portions extending from the bag to 105 the handle or shoulder strap portion, and quadruple portions throughout the said handle or strap portion with six ply portions at the middle of said handle portion, for the purpose described.

EDWIN L. HENDERSON.
